APPARATUS FOR PRODUCING PULP FROM
CELLULOSIC MATERIAL

James Brookes Beveridge, Westmount, Quebec, Canada, Richard Dunlap Kehoe, Hadlyme, Conn., and Alphonse Surino, Bronxville, N. Y., assignors to Paper and Industrial Appliances, Inc., New York, N. Y., a corporation of New York

Application November 21, 1942, Serial No. 466,410

1 Claim. (Cl. 92—6)

1
This invention relates to the recovery of individualized fibers in a pulp mass, such as are useful in the making of paper, wall board, dry felts, and the like. In the recovery of such fibers it is important not only that they be individualized without harmful loss of natural fiber length, but that the fibers be substantially delignified, that is freed of the layer of lignin and other binding material that surrounds the fiber proper, since the removal of that layer renders the fibers capable of fibrillation, that is of being bewhiskered by the formation on them of branch fibrillae. The branch fibrillae cause a stronger interlocking of the fibers into a web, and thus make a denser and stronger end product.

Consequently, this invention may be said to relate to the kind of production of fibrous pulp from cellulosic material, whereby the pulp is treated by attrition effects as it passes between the abrading faces of a pair of companion discs in a rotary refiner to effect de-fibration of the pulp following a conditioning or retreatment performed upon the raw or starting material, for instance ligneous material such as wood chips or wood waste or a mixture of both, or a mixture containing sawdust, or other fibrous materials such as flax, wheat and other straws, grasses, bagasse, or linters.

As one step in the attainment of these objectives, it has been proposed to make use of the apparatus of the patent to Asplund No. 2,145,851 which practices the process of the Asplund Patent No. 2,008,892. The inventions of these two patents are characterized by maintaining in a pressure chamber certain temperature and pressure conditions. The raw cellulosic material is pressure-fed to the chamber to be de-fibrated in an attrition mill, while still subject to such temperature and pressure conditions. After passing through the de-fibering mill, the resulting so-called Asplund pulp is released from the pressure environment by using the pressure to blow pulp into a trap chamber having alternately operated valves, from which it passes into an outside space that is exposed to atmospheric pressure.

A further step towards attaining the objective of improved fiber characteristics, such as flexibility, pliability, toughness and strength, as well as full fiber length, was made by way of improving the Asplund apparatus and treatment method in the manner disclosed in the copending patent application of Beveridge and Kehoe, Serial No. 351,670, now Patent No. 2,323,194, and Serial No. 484,444, now Patent No. 2,422,522. These im-

provements cover apparatus and process characterized by changing the temperature-pressure treatment chamber to include a chemical-bearing saturated steam atmosphere with positive means for impelling the cellulosic material therethrough at a controlled rate while in non-flooded condition, wherein the chemical has lignin solvent action so that the lignin content of the material is substantially lessened, as the individualized fibers are thus more effectively freed of it. The fibers are thus rendered susceptible to fibrillation. The fibers obtained by these improvements upon the Asplund method and apparatus will herein for convenience be termed improved Asplund fibers or as a fibrous pulp they may be termed improved Asplund pulp.

Preceding the present invention we have observed and found that in addition to its outstanding fiber characteristics the improved Asplund fiber pulp acquires a sleekness, slipperiness, or soapiness, perhaps due to the chemical treatment that accompanies the temperature-pressure treatment, and consequently the pretreated pulp develops a tendency to pass or slip past the attrition faces in the rotary refiner without receiving its full or adequate share of the refining or de-fibration treatment. We have also observed that the pressure under which the pulp is discharged from the refiner and from the system appears to encourage, at least momentarily, this phenomenon. In other words, certain otherwise desirable characteristics of the improved Asplund fiber are attained at the price of a somewhat lowered effectiveness in the operation of the refiner.

Therefore, this invention revolves about the de-fibering attrition mill through which pulp passes that has the aforementioned characteristics. Such a mill comprises a casing which houses two discs having abutting abrading faces, and of which one is stationary and the other is adapted to rotate. Material from the heat and pressure environment is fed to the center of the stationary disc and then it is defibered between the stationary disc and the rotating disc, while still under the heat and pressure conditions. The discs are of cast metal and are provided with peripherally disposed segments which have abrasive constituents.

It is a general object of this invention to improve the effectiveness of the mechanical refining or de-fibration or attrition step with respect to a fibrous pulp having the aforementioned characteristics.

Whereas the copending patent applications Se-

rial No. 351,670, and Serial No. 484,444 disclose an apparatus arrangement and process respectively, for producing fibers possessing the aforementioned characteristics of the improved Asplund fiber, and whereas these pending applications are in turn based upon the apparatus and procedure laid down in the aforementioned patents to Asplund, the corresponding apparatus and process are herein represented by way of illustration, to have the invention appear in a proper environment. It is the best and most effective practical application of this refiner improvement that we are aware of at present, but it is not to be considered as a limitation to the broader aspects of this invention.

For the purpose of dealing with this invention and for convenient identification, this improved de-fibrating mill will herein be termed as a stock retarding or self choking de-fibrating mill or refiner.

The original Asplund process may benefit from the operation of a de-fibrating mill that is improved in accordance with this invention which compensates for the tendency of pulp passing through the mill too fast during periods of pulp discharge, when steam from the pressure system momentarily expands through the de-fibrating mill and blows out the pulp.

In distinction from conventional cellulose digesting or cooking process in which the material is submerged or flooded with a liquor that has the property of loosening those substances in the wood that tend to bind the fibers together, the Asplund process and apparatus provide for a conditioning treatment, that is preliminary softening or partial dissolving or disintegration of the lignin or binding matter in the wood chips or ligno-cellulose material, and a subsequent mechanical de-fibration or refiner treatment to take place in a steam atmosphere, that is under certain temperature and pressure conditions.

It has operated successfully in a temperature range from 212° F. to 350° F. at a superatmospheric pressure corresponding to saturated steam of those temperatures, and pressures of 150 lbs. to 160 lbs. have been found acceptable.

Steam treatment under such conditions is said by Asplund to require a period of something less than 60 seconds and on the average of 40 to 50 seconds, to cause softening of the middle lamella of the ligneous material, (that is in effect the binder constituent for holding the fibers together in bundles) so that it can be separated into fibers when subjected to the action of the de-fibrating mill.

Under such process conditions the Asplund apparatus is adapted to absorb material or material mixtures of a grade, type or fineness, for instance sawdust or the like, that are not ordinarily acceptable for use in the conventional cellulose, digesting and cooking steps.

The Asplund apparatus is capable of continuous operation, since the ligno-cellulose material or wood chips are pressure fed against and into the steam pressure atmosphere mentioned in the interior of the Asplund treatment system. In order to introduce the wood chips into the pressure system, a plunger feeding device may be used whereby the wood chips are compressed or briquetted, so to speak, or a continuous screw feeding device is employed whereby a continuous strand or plug of the compressed material is forced directly into the pressure treatment system. The feed pressure exerted upon the material by the feed devices forming the plug is suffi-

cient to seal off the steam at the feed end of the system. Once inside the pressure treatment system the wood chips are first subjected to direct contact with the steam and then fed within the pressure system to a rotary refiner or de-fibrater. The finished or de-fibrated stock leaves the steam pressure system by way of a trap space having an inlet and an outlet valve that are operated in alternation. The inlet valve opens while the outlet valve is closed, to admit de-fibrated pulp from the refiner into the trap space. The inlet valve then closes, whereupon the outlet valve opens to discharge the contents of the trap space into the atmosphere. After the outlet valve closes on the thus emptied trap space, the inlet valve opens again, allowing the steam in the system to expand through the refiner into the trap space as the latter refills with finished de-fibrated pulp from the refiner.

20 The Asplund system of treatment is improved in accordance with the disclosures of the aforementioned copending applications by modifying or elaborating upon the pretreatment or conditioning phase in the temperature-pressure system, whereby delignification of, or removal of binding matter from the fibrous material is carried to a point unattainable with the Asplund process, so that not only will the fibers thereafter be effectively individualized without substantial loss of length, but also be rendered susceptible to becoming fibrillated. This will herein be designated as the improved Asplund process.

The modified or improved Asplund conditioning treatment just referred to comprises passing the 35 wood chips under mild stirring at a controlled rate along a substantially horizontal path through a special detention or reaction treatment space or chamber in which a steam atmosphere of suitable temperature-pressure conditions is maintained while imposing upon the material thus being detained a supporting delignifying chemical treatment. While the length of the period of treatment allowed for by Asplund is dependent upon the construction and capacity of the apparatus and under the conditions variable only within relatively narrow limits, with the improved Asplund process the factors of pressure, temperature, detention time, rate of stirring and the degree and timing of the chemical treatment 40 become variables controllable relative to one another, and in such a manner that the operation is more flexible, and conductable within wider limits, and so that optimum results may be obtained with respect to the quality of the end product as well as with respect to the conduct of the process itself. A chemical or chemicals introduced or atomized into the detention zone, have a supporting or intensifying solvent action upon or are capable of rendering soluble the resins, 45 lignin, and other binding matter contained in the cellulose material being thus treated, but especially the lignin.

The chemical may be organic or inorganic, or 50 may be acid or alkaline. It may be sodium hydrate or other sodium compound, or a mixture thereof. It may be a sodium acid sulphate, a free acid, an oxidizing or wetting agent. The chemical may be supplied to the chips or starting material in any desirable phase, namely solid, liquid or gaseous or in the form of vapors, either 55 directly into the system or the chips may be pre-saturated or pretreated before being fed into the system.

In view of the foregoing, it is a more specific 60 object of this invention to design a rotary refiner

or de-fibrating mill in such a manner that it will retard the passage of a sleek pulp through the refiner sufficiently for controlling or at least retarding the rate at which pulp is passed through the disc-bearing de-fibrating mill, to avoid a premature release of pulp from the system before it is thoroughly de-fibrated.

Another object is to avoid inadequate detention of the material in the de-fibration treatment phase, when that inadequacy is due to the pressure discharge of the material from the refiner, that is when the material is blown through the refiner because of the pressure in the system.

In setting up this problem and contemplating its solution, we have visualized that the very rotation of the refiner should dynamically set up counter-acting or self-choking reactive forces effective upon the pulp in such a manner that its passage through the refiner, that is, its passage between the attrition discs and past the attrition faces, will be sufficiently retarded.

Features of this invention find embodiment in the design and arrangement of the grinding faces of the de-fibrating discs, and especially in the manner in which they are grooved. That is to say, the grooves are directionally disposed in such a manner that there is effected a relative retardation of the pulp passing outwardly between the discs.

Specific features therefore are found in the layout and configuration of the grooves and lands of the attrition discs or bodies. According to one feature the grooves or lands have a generally curved configuration with the convexity of the curves facing opposite to the direction of rotation of the refiner disc. The curvature thus is opposite to what it would be in the vanes of a centrifugal pump. In this way there is set up a self-choking effect or reactive force upon the pulp passing over the attrition faces and through the narrow clearance between the refiner discs and through the grooves, and this effect or reactive force intensifies with the speed of rotation.

We have furthermore observed that incident to the opening of the inlet valve leading to the discharge trap space, the steam in the pressure system tends to expand at least momentarily through the clearance between the refiner discs into the trap space, as the trap space at the moment of opening of the inlet valve has in it the low pressure of the outside atmosphere since material from the trap space has previously been discharged through the outlet valve into the open. The momentary expansion of the steam pressure through the refiner, that is by way of the pulp filled clearance between the refiner discs and through the grooves into the trap space, enhances the tendency of sleek pulp to pass through the de-fibrating zone of the refiner without receiving its potential full share of de-fibrating treatment. Consequently another problem is to reduce or compensate for the effects upon the pulp movement of such steam expansion. A feature therefore resides in correlating the characteristics of the de-fibrating discs with the pressure of their environment that blows material through and from the discs when the pulp is discharged or released from the pressure system.

Another feature lies in the provision of means for equalizing at least to some extent the pressure differential that is momentarily set up between the inlet and the exit of the refiner due to the flow restriction or obstruction represented by the pulp filled clearance between the refiner discs.

Therefore, according to that feature, there is provided a pressure equalizing connection to compensate for the aforementioned momentary pressure differential between the inlet and the exit side of the refiner.

The invention possesses other objects and features of advantages, some of which with the foregoing will be set forth in the following description. In the following description and in the claims, parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

For example, while the novel groove pattern on 20 the de-fibrating discs, that constitutes a part of this invention, is herein shown to comprise curved groove portions disposed in the outer zone of the disc, it should be understood that the invention is not limited to this specific embodiment as to 25 shape. That is to say, the characteristic feature of the groove pattern may be more broadly defined as comprising groove portions located in the outer zone of the discs, and disposed at an angle with respect to further inwardly located adjacent 30 groove portions, the relative angularity being such as to set up a scooping or self-choking or retarding effect with respect to the passage of the pulp between the de-fibrating discs.

The novel features considered characteristic of 35 our invention are set forth with particularity in the appended claim. The invention itself, however, both as to its organization and its method of operation, together with additional objects and advantages thereof, will best be understood from the following description of a specific embodiment when read in connection with the accompanying drawings in which

Fig. 1 is a side view of an apparatus for treating 45 fibrous raw material according to the improved Asplund process, by pre-treating and then de-fibrating the material in a steam atmosphere of certain temperature pressure conditions while superimposing thereon chemical treatment effects, 50 the apparatus comprising the improvements in the de-fibrating mill whereby pulp thus preconditioned is more effectively de-fibrated with the mill housing partly broken away to show the novel groove pattern on the attrition discs.

Fig. 2 is a front view of the apparatus of Fig. 1, 55 with parts broken away.

Fig. 3 is a top view upon the apparatus of Fig. 1 along the line 3—3, with one end portion of the 60 detention or reaction treatment chamber broken away.

Fig. 4 is a section through the apparatus of Fig. 1 along the line 4—4, showing also a top view of the de-fibration mill and of an automatic discharge trap valve mechanism associated therewith.

Fig. 5 is an enlarged detail section along the line 5—5 of Fig. 1 of the discharge trap for the de-fibrated pulp, with inlet and outlet valve therefor.

Fig. 6 is a greatly enlarged part-sectional side view of the de-fibration mill showing a section through the de-fibrating discs and segments, and provided with a novel pressure equalizing connection on the housing.

Fig. 7 shows the improved pattern comprising

novel curved grooves in the abrading face of a de-fibrating attrition disc.

In the drawings, the numeral 10 represents a chip bin or hopper to which the chips of wood or the raw cellulosic starting material are supplied, from which the chips pass to a horizontal cylindrical casing 11 in which operates a screw or other conveyer or pusher 12 operated by a suitably driven reduction gearing 13. This arrangement is mounted upon a base 14 supported from a floor 15. The chips are expelled from the casing 11 past a weighted valve 16 into a steam chamber 17 to which steam is supplied through the medium of a valved steam line 18. To the steam line 18, there may be supplied, if desired, one or more chemicals through the medium of a valved chemical line 19 connected to some high pressure line.

From the steam chamber 17, the chip stock or fiber stock is passed into a reaction chamber or pressure-temperature treatment zone, indicated generally by C. Such a chamber comprises a vertically disposed entrance or neck section 20 for receiving the chips or stock from the steam chamber. The neck or pipe 20 is connected to a substantially horizontally disposed top or primary chamber portion or pipe 21 that forms with the neck 20 an inverted T. This top chamber 21 has a closure plate 22 at its right hand end (Fig. 2) and a somewhat similar closure plate 23 at its opposite end. Adjacent each end of the chamber 21, there are provided vertically disposed pipes 24 and 25 respectively. These pipes are connected to similar pipes 26 and 27 respectively that are upstanding from a secondary or lower, horizontally disposed chamber portion or pipe 28 in a manner that aligned pipes 24 and 26, and 25 and 27 comprise passageways for stock to pass from the primary horizontal chamber 21 to the secondary chamber 28.

Secondary chamber 28 has its ends closed by plates 29 and 30 respectively. At the central portion of chamber 28 there is a vertically disposed outlet pipe 31. In the primary chamber 21 there is provided a screw or ribbon conveyer 32 whose flights or ribbons are so arranged that stock entering the chamber from neck 20 is split or spread, with some being impelled toward each end of the chamber, as shown by the arrows in Fig. 2. Since the cross-sectional areas of the chambers 21 and 28 are not less than that of neck pipe 20, the stock spreads out in the chambers and its level rarely extends above the axis line of the chambers.

33 and 34 represent suitable drive means for operating and conveyers 32 in the primary chamber 20 and a ribbon conveyer 35 in the secondary chamber. Ribbon conveyer 35 is arranged to convey stock from the ends of secondary chamber 28 toward its center outlet 31. The ribbons are interrupted at 36 in order to facilitate the passage of the stock into the outlet pipe 31. Aligned with vertical pipes 24 and 25 of the primary chamber are inspection or hand-hole cleanout pipes 37 and 38 respectively.

The stock or chips passing through reaction chamber C via outlet pipe 31 may go to further treatment, or it may be passed through a further reaction chamber that is a duplication of the reaction chamber C and therefore herein not shown but broken away except for its inlet connection 31^a and its outlet connection 31^b, while the location of that additional chamber as a whole within the system is indicated by the letter C'. A pressure-equalizing pipe 85 extends from the inlet end of the reaction chamber C to the outlet end of reaction chamber C'.

From outlet pipe 31^b the pre-treated material or stock falls into a compartment 39 in which operates a discharging screw or ribbon conveyer or expeller 40 that extends into a pipe section 41, and is suitably driven as by gearing 42 and a motor 43 mounted on a base 43^a.

The pipe 41 connects centrally or axially with the casing of a de-fibrating mill or refiner 44 of the rotary disc type, that embodies special improvements pertaining to the de-fibrating step in the apparatus arrangement of this invention. A greatly enlarged part-sectional detailed view of the de-fibrating mill 44 is shown in Fig. 6, and a face view of improved abrading surfaces on the attrition segments of the mill is shown in Fig. 7. The housing of the mill has an inlet portion or flange 45 that connects with the pipe 41.

Opposite therefrom and coaxial therewith the housing has mounted therein a horizontal impeller shaft 46 provided with a tapered end portion 46^a extending inside the housing, upon which is keyed a rotary disc 47 from the circumference of which extend radial vanes 47^a; the disc 47 in turn carries an annular attrition plate 48 held in place upon the disc 47 by means of a cap nut 49 screwed upon the reduced and threaded extreme end portion 50 of the shaft 46, which cap nut is provided with lugs 51 or the like for tightening it. This cap nut has an outer cone shaped configuration 52 to help streamline the course of the pulp flowing through the inlet portion 45 into the mill. The rotary attrition plate 48 has an inner zone P that is provided with ribs 53 for guidance and preliminary attrition, and an outer zone Q being shaped to have mounted therein abrading segments 54 which in turn are provided with a novel pattern of grooves extending outwardly in the general direction of the ribs or grooves 53.

40 The segments 54 are shown to be secured in place upon the attrition plate 48 in a known manner by means of bolts and nuts 55. The rotary abrading segments 54 cooperate face to face with stationary abrading segments 56 that are substantially similar to the rotary abrading segments 54. A more detailed description of the novel groove pattern in both these segments that constitute a part of this invention, will be more specifically described below. The stationary segments 56 are held in place by means of bolts 57 upon a stationary attrition plate 58 that is fixed to the housing of the mill by means of bolts 59, and it has auxiliary ribs or grooves 59^a for preliminary attrition that are somewhat shorter than the corresponding grooves in the rotary attrition plate 48, since the stationary attrition plate 58 has a central opening to match the pulp inlet that is larger than the central opening of the rotary attrition plate 48. The housing of the mill is split along a plane extending transversely of the axis of rotation of the shaft 46, and accordingly it comprises a housing portion 61 that is shown to be integral with the inlet flange 45, and a housing portion 62 in which the rotary shaft 46 has its bearing, both housing portions 61 and 62 being bolted together as at 63. As a further specific refinement there is provided upon the housing of the mill a pressure equalizing connection 64, the function of which will be described further below in connection with a description of the operation of the apparatus.

The impeller shaft 46 of the mill is driven through a chain and sprocket drive 65 and a motor 66.

75 Pretreated pulp entering the mill through the

inlet portion 45 and being passed outwardly between the opposed or abutting abrading segments 54 and 56 whereby it is de-fibrated, leaves the mill housing through a lateral outlet connection 67 that is provided upon and shown to be integral with the portion 62 of the mill housing. From there the de-fibrated pulp passes through a sequence of elbows 68, 69 and 70 in to a trap space 71 represented by an S-shaped pipe portion 72, and from there through a bent outlet discharge portion or pipe 73. At each end of the trap space or S-shaped pipe there is provided an inlet valve V₁ and an outlet valve V₂ respectively.

The inlet valve V₁ is shown to comprise a seat member 74 interposed between the flanges of the elbow portion 70 and of the S-shaped pipe portion 72, and an associated valve member 75 having a valve stem 76 extending through the wall of the S-shaped pipe or trap space. The outlet valve V₂ is substantially identical to the inlet valve V₁ in that it comprises a seat member 77, a valve member 78, and a valve stem 79 that extends through the wall of the bent discharge pipe 73. A mechanism comprising the valves V₁ and V₂ is known of itself and described in the patent to Asplund (No. 2,145,851), and therefore a mechanism for automatically actuating these valves in alternation is not herein shown except diagrammatically as indicated by the letter M.

The function of that valve mechanism is such that the valves V₁ and V₂ operate in alternation, that is to say the valve V₁ opens while the valve V₂ remains closed, so that pulp discharging from the de-fibrating mill may be admitted into the trap space 71 accompanied by an expansion of the pressure atmosphere within the mill into that trap space. The inlet valve V₁ then closes, whereupon the outlet valve V₂ opens to permit the trapped volume of pulp to discharge through the bent pipe 73, as the trapped pressure from the trap space 71 expands into the open, helping the discharge.

With the refining mill subjected to the pressure environment that is maintained in the pretreatment phase of this apparatus embodiment, it will be understood that there is a tendency of the pressure from the mill to momentarily blow de-fibrated pulp into the trap space 71, since at the moment that the inlet valve V₁ opens, the back pressure in the trap space 71 is substantially equal to the lower pressure of the outside atmosphere due to the outlet valve V₂ having previously been opened and closed during the discharge of a preceding batch of trapped pulp.

Referring to Fig. 7 there will now be described the layout of a novel grooved pattern on the abrading faces of the improved abrading segments.

One such segment designated in Fig. 7 by the letter Z, has an outer zone S that is occupied by grooves 80 having a substantially straight inner end portion and a curved outer end portion, and also occupied by somewhat shorter or medium long curved grooves 81, and by still shorter or short curved grooves 82. In distinction from the short grooves 82 and the medium long grooves 81, the first mentioned grooves 80 will herein be termed the long curved grooves. This segment Z further has an inner zone R occupied by substantially straight although slightly tapered outwardly extending long grooves 83 alternating with similar although somewhat shorter straight grooves 84 herein called the short straight grooves.

It will be seen that the long curved grooves

80 of the outer zone S are staggered with respect to the straight-long and medium-long grooves 83 and 84 respectively of the inner zone R, and that both the curved grooves 80 and the straight grooves 83 and 84 extend relative to each other in such a manner that the inner end portion of the curved grooves 80 and the outer end portions of the straight grooves 83 and 84 occupy an intermediate zone T represented by the overlap between the outer zone S and the inner zone R.

It will be seen that in this arrangement or pattern the straight long grooves 83 register with the curved short grooves 82, while the straight short grooves 84 register with the curved medium long grooves 81. The curved long grooves 80 are out of registry with the straight grooves 83 and 84 and are consequently disposed so as to extend into the respective spaces therebetween.

Operation

The effect of the practice of this invention in comparison with either the original Asplund method or the improved Asplund method, may be expressed in the following tabulation:

25 Undue acceleration of passage of the pulp past the abrading faces of the de-fibrating discs (as is responsible for inadequate de-fibration) may be caused by any one or any combination of the following factors:

30 (a) The centrifugal force exerted upon the pulp passing through the mill by the rotation of the disc,

(b) The pressure or steam atmosphere under which the de-fibrating in the mill may be allowed to take place, and which pressure blows the pulp out of the mill when discharging,

(c) The slipperiness, soapiness or sleekness which the pulp acquires due to pretreatment in a chemical-bearing steam atmosphere in the de-fibrating mill.

Therefore, according to this invention, a retardation of the rate of pulp passage past the abrading faces is desirable.

45 (1) In the original Asplund method and apparatus (according to the aforementioned patents) because of the presence of the above factors (a) and (b),

50 (2) In the Asplund method as improved by Beveridge and Kehoe (according to their aforementioned copending patent applications) due to the presence of factors (a), (b) and (c).

55 It has been stated that according to the aforementioned Asplund patents, unsubmerged lignocellulose materials such as wood, straw, flax and the like have been subjected to steam heat, moisture and superatmospheric pressure for softening the middle lamella, and the material was then put through a grinding or de-fibrating refiner while still subject to the temperature-pressure conditions.

60 This produces an improved fiber product, but as the fibers when subjected to grinding still contained their lignin sheath, layer or armor, the grinding seemed to break or shorten the fibers as it had little or no effect on removing the lignin sheath from the fibers. Still, when practicing this Asplund method in conjunction with the improved de-fibration step according to this invention, the benefit thereby obtainable is due to the fact that the improved de-fibration

65 operation tends to compensate for the above identified factors of (a) centrifugal forces in the grinding mill, and (b) the steam or blowout pressure, both of which otherwise would tend to reduce the effectiveness of the de-fibration step.

70 75 The fibers exhibit the particularly desirable char-

acteristics of natural strength, toughness and flexibility, without substantial impairment of the natural fiber length which it is highly desirable to preserve as far as possible through the operation.

What seems to happen in the treatment method according to that embodiment is that the middle lamella, that is in effect the binder constituent for holding the fibers together in bundles, is softened or otherwise made amenable to the subsequent refining or grinding or de-fibrating operation whereby the bundles of fibers are pulled apart or individualized. Moreover, this treatment appears to overcome an ever present difficulty, namely the breakage and shortening of the fibers, so that they retain substantially their full length. Also it appears that this treatment not only affects the natural binder substance or middle lamella, but in distinction from the original Asplund process that involves no chemical along with the steam, it furthermore cleans the individual fibers of the lignin and any other gums or waxes as well that surround them like a sheath or armor. Yet, the slipperiness of the pulp due to this treatment and whereby the relative effectiveness of the de-fibrating operation is liable to be reduced, is at least partially compensated for in the practice of this invention.

This treatment further involves the use of appropriate chemicals to establish and maintain certain pH conditions in the material being treated, as well as appropriate dilution conditions and concentrations of the chemicals. For producing individualized fibers having the aforementioned desirable characteristics from ligno-cellulose material, the treatment further involves the special correlation with each other of such operating factors as moisture, temperature, pressure, amount of chemicals used, their character and their concentration. It also involves as another factor to be correlated, the time element, so that the material is passed through the pre-treatment section at a controlled rate while being continually redistributed whereby there is discouraged localized overheating, localized degrading of the fibers and discoloration.

For its particular results as to fiber characteristics this treatment also involves maintaining in the pretreatment zone a steam- and chemical-containing atmosphere at super-atmospheric pressure and an atmosphere such that moisture and soluble chemicals therein are maintained atomized. At the same time it provides for an enlarged conduit section or extended path of treatment along which the material being treated in that atmosphere can be spread out to overcome compacting tendency, and it provides means for positively impelling the material through the conduit in a manner whereby the material is continually turned or rolled over so that fresh surfaces of the material are continually exposed to the treatment atmosphere. In view of the importance of the factor of detention time in conjunction with all the other factors, the rate of passage of the material through the treatment conduit according to this embodiment, is controllable by adjusting the rate by which the impelling means are operated.

The environment of the material or chips in the treatment zone is kept so that there is a minimum of liquid therein and a maximum of vapor. The steam used may be supplemented with one or more chemicals that aid in the de-lignification of, and other treatment effects upon the wood chips or other starting material, or the material

can be supplied with the chemicals prior to its introduction into the reaction chamber.

After grinding, the de-fibrated mass is subjected to washing as soon as possible so that excess chemicals, middle lamella, lignin solutes, color and other impurities are removed from the mass before they are reabsorbed by the fibers. Such reabsorption does not appear to take place in the mill itself while a suitable temperature-pressure atmosphere is maintained therein. But after the stock is released from the pressure and temperature of the mill, it should be quenched and agitated rapidly with wash water so that the solutes and other impurities are washed free of the fibers before they can congeal on or around the fibers, for these impurities seem to be thermoplastic.

According to this embodiment, the cellulose starting material is pressure fed in the form of substantially dry chips of wood that are compressed into plugs as they are pressure fed into a reaction chamber that has an atmosphere of steam ranging from 212° F. to 390° F. at pressures corresponding to saturated steam of the temperature used. After the chips, flax, straw or other starting materials have been introduced into this environment, they are passed to a reaction chamber that is substantially horizontal and has a cross-sectional area that is larger than the preceding zone, and is provided with mechanical means, such as a screw for impelling the chips therethrough whereby the plugs of introduced chips disintegrate into individual chips, and the chips are spread out so that a maximum of their surface is exposed and continually re-exposed to the environment of steam, temperature and pressure, and of chemical. Indeed, in the embodiment shown the chips are raked or impelled first in one direction and then in another, in an enlarged conduit that is only partially filled with chips.

In making use of the apparatus thus described, the ligno-cellulosic material to be treated, such as chips of wood from deciduous and coniferous trees, or cut straw, flax, bagasse and the like, is supplied to the hopper 10 whence it is compressed and compacted in casing 11 by means of screw conveyer 12 into plugs that are pressure-fed past weighted valve 16 into the steam chamber 17 that is in the nature of a pre-heater, under conditions that the feeding does not prevent the maintaining of the heat, steam and pressure conditions in the treatment chamber shown generally at C (and additionally if desired C'). Steam for providing the heat and moisture and pressure conditions in the chamber is pumped thereto through pipe 18. If chemicals are to be introduced directly, they are pumped through pipe 19. Since it is desirable that they be atomized, an atomizing device A is made use of where the chemical conducting pipe 19 joins the steam pipe 18.

The chips or other material is forced against the high pressure in the chamber, by the pressure feeding device or screw 12 along the steam chamber or conduit 17 until it falls down neck 20 into enlarged chamber 21. The pressure compresses the wood to substantially twice its normal density. In this chamber, the material spreads out since it does not nearly fill the cross-sectional area thereof, and is impelled by screw conveyer 32, under conditions that tend to uncompact or decompress the material and also to roll the material over and over upon itself for continually exposing fresh surfaces thereof

to the atmosphere of the chamber. The material then falls to the lower chamber or conduit 28 where another screw or ribbon conveyer 35 continues the continual exposing of fresh surfaces and impels the material to fall through neck 31, either to a further reaction chamber C' or directly to compartment 39, depending upon whether or not a second reaction chamber C' be used. The speed of impelling of the material, and thus its time of transit through the reaction chamber C is controlled by the pitch of the rate of rotation of the screw conveyers 32 and 35.

By the treatment of the material or stock in the reaction chamber C that has an atmosphere of high temperature, high pressure, steam and chemicals wherein the stock is agitated in non-submergence at intensity less than that for causing de-fibration, what happens is that the heat and moisture softens the middle lamella or binder of the fiber bundles and there is sufficient agitation of the stock in the chamber to permit the bundles of fibers to be exposed to the action of the atomized chemical, since the atmosphere of the chamber is like a mist or fog of steam and chemical. Each fiber has a sheath, layer or armor of lignin that nature seems to have provided to protect the more soluble lignin-complex that exists between the cellulose core of the fiber and the lignin sheath. This complex contains a heterogeneous mixture of lignin, hemicellulose, and carbohydrates such as sugars, or more particularly pentosanes and polysaccharides. The lignin of this complex seems to be more soluble than the lignin of the fiber enveloping sheath. Therefore, the lignin sheath must be made pervious to the steam present for dissolving the soluble constituents of the internal complex. This is accomplished by making use of chemicals that render that lignin in its different forms soluble under the conditions of heat, pressure and moisture prevailing in the reaction chamber. However, this rendering of the lignin soluble involves a time factor and this is provided for by the effective length of the reaction chamber, the rate of passage through which is controlled by the screw conveyers. Since the stock is not submerged in liquid, the chemical reaction between the chemical and the lignin takes place between a solid and a wet gas or vapor. Therefore, fresh surfaces of the solid must be continually brought into contact with the gas, and the distributing action of the screw conveyer accomplishes this result.

As the stock leaves the reaction chamber, it comprises a mixture of bundles of fibers, lamella, and chemicals, lignin, and some other impurities including color constituents, in solution phase. By lessening the lignin content of the fibers, it has been found that they are amenable to the de-fibering action of the grinding station with little or no tendency to become shortened or otherwise degraded, for it is their content of lignin sheathing that heretofore has caused such unsatisfactory results from the refining or de-fibering station.

In the reaction chamber, there is maintained a super-atmospheric pressure of from 100 to 150 pounds per square inch, although the yardstick to be used is to maintain a pressure that yields a condition in which the wood of the chips is thoroughly impregnated. The temperature maintained varies with (1) whether or not chemicals are used, and (2) the degree of cleanliness required of the fibers. If no chemicals are employed, the temperature used is usually be-

tween 365° and 390° F., whereas, if chemicals are employed, good results have been attained with a temperature as low as 270° F.

With respect to the chemicals that can be used, they divide themselves generally into two groups, those that are acidic in character, and those that are alkaline. Certain factors must be borne in mind, in determining which to use. The hemicellulosic constituents of the wood are subject to hydrolysis and this is accomplished in either acid or alkaline medium. Also, the removal of incrustants varies with the kind and concentration of chemicals employed. For example, soda and sulphate liquors have been found to be much more reactive to hemicellulosic material during the early stages of cooking than they were to lignin. Also, soda and sulphate liquors remove the intercellular substance, between the primary walls, very rapidly, but do not attack the cell wall lignin to any great extent until the former is nearly completely removed. Sulphite liquor does not have this selective action, but removes both intercellular and cell wall lignin, at about the same rate, though more slowly than the rate at which alkaline liquors dissolve lignin.

Chemicals that can be used comprise:

Sodium hydroxide, sodium carbonate, sodium sulphite, or any combination of these chemicals together, e. g. sodium hydroxide and sodium sulphite
Sulphur dioxide
Sodium bisulphite—sulphur dioxide in excess
Calcium bisulphite—sulphur dioxide in excess
35 Magnesium bisulphite—sulphur dioxide in excess
Ammonium hydroxide
Ammonium sulphite
Ammonium bisulphite
Sulphuric acid, nitric acid, or any organic or mineral acid in general

The concentration of the chemicals used ranges from 0.5 pound to 4 pounds per gallon. The usual concentration used is 2 pounds per 45 gallon or approximately 20% concentration by weight of chemical. The usual concentration by weight of chemical in the reaction chamber is 5%. These figures are based on a feed rate of 1000 pounds of chips per hour on the bone dry basis, a steam consumption of 700 pounds per hour with approximately 500 pounds per hour condensed in the chamber, and a chemical feed of 10 per cent based on the bone dry chips fed.

The dilution in the reaction chamber including condensed steam and moisture in fibrous material is 50-95%.

The dissolving action of the chemicals is greater for increased acidity or alkalinity. The pH values of the effluent from the de-fibered material may be taken as a measure of the extent to which the chemicals employed are consumed or absorbed. This represents an important control method for the amount of chemicals to be added to the raw material in the apparatus. Conductance measurements may also be used for quick control.

It can be said that our prevailing pH range when acidic chemicals are used is from 1 to 6 and when alkaline chemicals are used, from 7 to 12. But normally, our range is between 3 and 9. When acids are used, the cooking starts very acid but during the reaction time, the acidity is absorbed by combining with the lignin present so that the actual pH of the discharging fiber increases.

15

In the same way, if an alkali is used, whatever pH is started with the pH of the finished fiber is less.

The time of passage or transit of the stock through the chemical atmosphere of the reaction chamber can be used somewhat as a micrometer adjustment to supplement the quantity of chemicals added. On the whole, the time of transit should be at least one minute and can be as long as sixty minutes. The reason for this is that the chemical reaction is a surface contact phenomenon and therefore the greater the surface contact, the greater the efficiency of the reaction. This is where the distributing and stock turning-over action of the screws of the reaction chamber are effective.

The stock in the reaction chamber must be protected from localized overtreatment or excessive breaking down or degrading of the fiber structure, so the chemical present must not be too strong or too highly concentrated. It may be said that by practicing the Asplund process without chemicals, a recovery of 93% of the wood input is recovered in fibers, whereas by the practice of this invention the yield of recovered fiber can be from 50% to 90%. The difference is accounted for mainly by the lessened lignin content of the fibers as yielded by the practice of this invention. The concentration of the chemical used is controlled by the amount of water or moisture added. The chips normally contain from 30-50% moisture, or for each part of dry material, they have from one-third to one-half part of moisture. With that as a starting point, steam and chemical solution is added to maintain in the atmosphere of the reaction chamber, a moisture content of between 50 to 95% of the material on a dry basis.

From the reaction chambers C and C' the stock passes into the outlet receiver or chamber 39 whence the screw feeder 41 feeds it to the de-fibrating mill 44. While the general structure and de-fibrating function of such a mill is substantially well known, its de-fibratory effect is improved or modified in the practice of the present invention because of the effect of the improved type or shape of the groove pattern provided on the grinding or abrading segments 54 and 56 that are rotary and stationary respectively. The novel groove pattern has its effect upon the process herein described as a whole, in that it retards the passage of the fibers through the attrition zone of the mill. This retardation is due to the curved configuration of the grooves 50, 51 and 52 on the attrition segments, since the curves are such that their concavity faces in the direction of rotation, and in their effect upon the pulp they might be compared to the effect of rotary scoops, that is contrary to the effect of the blades or vanes of a centrifugal pump.

This invention is not limited to fashioning both the rotary as well as the stationary segments in the same manner, and for instance, the one may have curved, and the opposite segments may have straight grooves. As one of a number of possible embodiments it is herein contemplated to have the curves of the stationary segments curved in a direction opposite to the curvature of the grooves on the rotary segments, the sense of both curves, of course, being that of having a relative 70 scooping or self-choking effect upon the pulp passing through the attrition zone.

The effect of the curvature of the grooves is to set up a reactive or choking force relative to the pulp passing through the attrition zone be-

16

tween the opposed segments, that is sufficient at least to partially compensate for those factors that tend to speed the fibers past the attrition zone in a manner whereby they are inadequately de-fibrated. Those factors are

- 5 (a) The centrifugal force due to the rotation of the rotary segments,
- (b) The steam pressure from the preceding reaction chamber that tends to blow pulp through the mill periodically as the discharge mechanism M operates, and
- (c) The slipperiness or soapiness or sleekness acquired by the stock because of the preceding chemical treatment in the reaction chamber.

15 Thus because of this invention there are combined all of the advantages of the improved fiber characteristics due to the improved Asplund treatment (whereby the reaction chamber as well as the subsequent mill operation take place under elevated temperatures and pressures of a steam-chemical atmosphere) with the effects of high grade de-fibration or individualization of the fibers.

20 The finished fibers leave the mill 44 by way of the outlet connection 61, and passing on through the elbows 68, 69 and 71, enter the trap space 71, and from there pass out of the pressure atmosphere to be washed and further treated. Due to the quickly alternating operation of the valves V₁ and V₂, the operation of the trap space 71 is such that the material discharges from the pressure system in intermittent although near-continuous flow. As the trap valve V₁ opens (the trap outlet valve V₂ being closed), the steam atmosphere expanding from the mill into the trap space blows a charge of the finished material into the trap space. The valve V₁ then closes, and when thereupon the trap outlet valve V₂ opens, the trapped material is discharged, the discharge being helped by the expansion of that portion of the steam atmosphere that has been trapped along with the material in the trap space 71. Due to the special drive mechanism M there is a rapid succession of such valve operating cycles.

25 30 35 40 45 50 55 The equalizing connection 64 between the inlet and the outlet end of the housing of the mill 44 may be employed for the purpose of reducing or compensating, at least partially, for the effect of the aforementioned factor (b); that is, the blowing-through effect of the steam pressure.

This specific compensatory effect may be adjusted or eliminated as the case may be, by means of a control valve (not shown) in the connection 64.

55 We claim:

60 Apparatus for the preparation of defibrated cellulosic fibers which comprises a closed treatment chamber, means for continually feeding cellulosic material thereto, means for continually supplying steam to the chamber for maintaining therein an ever-changing vapor body comprising steam having a temperature above 212° F. and super-atmospheric pressure adapted for conditioning said material in said vapor body for de-fibration, a refiner having a casing provided with an inlet for passing the so-conditioned material from said chamber to the refiner and whereby the casing communicates with the chamber while being subject to such temperature and pressure, 65 refiner discs face to face in said casing and rotatable with respect to one another with a clearance between the faces through which such material is impelled by the vapor escaping therethrough from the chamber, outlet means associated with the casing through which defibrated material is sub-

17

stantially continually emitted in suspension in the escaping vapor, conveyor means for mechanically controlling the rate of feed of the material from the chamber to the refiner discs, and retarding means substantially independent of the clearance setting of the discs providing grooves alternating with flat lands in the face of at least one disc and having a bend in the direction of the rotation of the disc for retarding the transit of the material relative to the flow rate of the escaping vapor so that a sufficient quantity of such material is detained sufficiently between the discs to have a defibrating action on itself within said clearance while minimizing the deterioration of fiber length.
